UNITED STATES PATENT OFFICE.

JOHN LEWIS WETTLAUFER, OF TORONTO, ONTARIO, CANADA.

CONCRETE-MIXING MACHINE.

1,109,097.

Specification of Letters Patent.

Patented Sept. 1, 1914.

Application filed March 3, 1911. Serial No. 612,042.

To all whom it may concern:

Be it known that I, JOHN LEWIS WETTLAUFER, of the city of Toronto, in the county of York, in the Province of Ontario, Canada, have invented certain new and useful Improvements in Concrete-Mixing Machines, of which the following is the specification.

My invention relates to improvements in concrete mixing machines and the object of 10 the invention is to so arrange for the dumping of the machine that it may be controlled from the back of the machine, where the material is received and thus dispense with an extra man usually employed at the front 15 to regulate the dumping of the drum.

My invention consists of an eccentric secured to the main shaft and a strap encircling the same and provided with a connecting rod, and a lever having a pivotal joint 20 connection to the rod, and a toggle joint connection to the drum frame, a clutch on the shaft and a suitable lever for throwing the clutch in and out as hereinafter more particularly explained.

25 Figure 1, is an end elevation of my concrete mixing machine showing the parts involved in my invention. Fig. 2, is a sectional plan with the drum partially broken away to exhibit the construction.

30 In the drawings like letters of reference indicate corresponding parts in each figure.

A is the main frame, which is supported on any suitable truck.

A' is the drum.

35 B are standard brackets and C is a tiltable drum frame, which depends from a trunnion shaft C' extending through the top of the standard brackets B. The trunnion shaft C' about which the drum frame tilts is between the drum and its frame, and is so 40 positioned as to bring the center of gravity of the drum and its frame as near the axis of tilt as possible when the drum is loaded.

C⁶ is a stud shaft journaled in bearing 45 brackets C¹⁴ on the drum frame.

C⁷ is a bevel gear mounted on the stud shaft C⁶.

C⁵ is a bevel gear mounted on the trunnion shaft and meshing with the gear C⁷.

50 C⁹ is a gear ring on the drum A'.

D is the main driving shaft. A spur gear is provided on this shaft D which meshes with a spur gear on the trunnion shaft C' from whence motion is imparted to the rotating means for the drum through the bevel

gear C⁵ on the trunnion shaft, the gear C⁷, the stud shaft C⁶, and so on to the drum. If preferred, I may make the spur gear on the trunnion shaft and the bevel gear C⁵ of one piece. E is a normally inoperative 60 eccentric located thereon and E' is the strap of the eccentric, which is provided with the usual connecting rod E² having a forked end E³.

F is a lever fulcrumed on the cross bar A^x and connected by a pin F' to the forked end of the connecting rod E³.

F² is a link pivotally connected to the frame C at its downwardly moving side and to the lever F and forming a toggle joint 70 with the lever.

G is a clutch of any suitable type for connecting and disconnecting the eccentric E from the power shaft D and H is an operating lever, which is provided with pins H', 75 which extend in the usual grooved collar of the clutch. By manipulating the lever H the clutch operates to throw the eccentric with its frame tilting means into and out of operation.

It will be seen that the lever H extends to the rear or feeding end of the drum and consequently is in control of the man, who is usually employed at this side of the machine. This man may by throwing the 85 clutch in provide for the ready dumping of the drum as the eccentric will be then thrown in motion and will impart the necessary pull through the lever F and toggle jointed link F² to the discharge end of the frame, thus 90 throwing it down and the drum likewise, so as to discharge the contents of the drum. The lever may be thrown in permanently and in this case the drum will be tilted periodically, this depending upon the speed 95 at which the shaft rotates, which may be, of course, predetermined according to the rapidity with which it is found that the drum may be filled with material.

By having the pivotal axis between the 100 drum and its frame it is possible to have the center of gravity of the drum and its frame, when loaded, fall very nearly within this axis, which means that the drum and its apparatus is so nicely balanced on its pivotal axis that even though it may contain a considerable weight of concrete material, it will take only a minimum of power to cause it to dump. This easy tilting feature, together 105 with the control of the dumping of the ma 110

chine at the feeding end carries out the object of my invention of securing a one-man operated machine.

What I claim as my invention is—

5 A concrete mixing machine comprising a main frame, a trunnion shaft, supports therefor on said frame, a tiltable drum frame depending from said trunnion shaft, a drum on said drum frame having opposite feed and discharge openings, the pivotal axis of said drum frame being between said drum frame and the drum thereon, the center of gravity of said drum and its frame,

when loaded, lying approximately within said axis, rotating means for said drum, a 15 power shaft, means coaxial with said trunnion shaft for transmitting power from said power shaft to said rotating means, normally inoperative tilting means for the drum frame, means for operatively connecting 20 said rotating means and said tilting means.

JOHN LEWIS WETTLAUFER.
